[57] **CLAIM**

The ornamental design for a locking unit for holding elongated objects such as ropes, bands or the like, as shown and described.

DESCRIPTION

FIG. 1 is a top plan view of a locking unit for holding elongated objects such as ropes, bands or the like showing our new design;

FIG. 2 is a top and front perspective view of thereof; FIG. 3 is a top, rear and side perspective view thereof, the opposite side and bottom of the locking unit are understood to be mirror images of the side and top shown;

FIG. 4 is a top plan view of a second embodiment of a locking unit for holding elongated objects such as ropes, bands or the like;

FIG. 5 is a top, front and side perspective view of FIG. 4;

FIG. 6 is a top, rear and opposite side perspective view of FIG. 4, the undisclosed bottom is a mirror image thereof;

FIG. 7 is a top plan view of a third embodiment of a locking unit for holding elongated objects such as ropes, bands or the like on a reduced scale;

FIG. 8 is a top, front and side perspective view of FIG. 7 on a reduced scale; and

FIG. 9 is a top, rear and opposite side perspective view of FIG. 7 on a reduced scale; the undisclosed bottom is a mirror image thereof.

FIG. 1**FIG. 2****FIG. 3****FIG. 4****FIG. 5****FIG. 6*****FIG. 7***

FIG. 8

FIG. 9
